UNITED STATES PATENT OFFICE.

JOSEPH H. JASPER, OF PHILADELPHIA, PENNSYLVANIA.

DUMP-WAGON.

Specification of Letters Patent.

Patented Jan. 27, 1920.

1,328,923.

Application filed March 26, 1919. Serial No. 285,223.

To all whom it may concern:

Be it known that I, JOSEPH H. JASPER, a citizen of the United States, residing at Philadelphia, in the county of Philadelphia and State of Pennsylvania, have invented 5 in certain new and useful Improvements in Dump-Wagons, of which the following is a specification.

One object of my invention is to provide 10 a dump wagon which will be particularly well adapted for use for clearing farm land or for any other purpose where it is desired to load material and in which it is necessary for the wagon to pass over rough and irregular ground.

Another object is to so construct my improved 20 wagon that the body portion can be easily tilted either into a dumping position or into a position in which rocks or other heavy material can be loaded.

Another object is to so make my improved 25 wagon that it will include means whereby heavy articles can be raised and lowered into the body portion without tilting the body portion if occasion demands.

A still further object is to make my invention of a strong and durable construction and so that it can be easily and cheaply manufactured.

These objects, and other advantageous 30 ends which will be described hereinafter, I attain in the following manner, reference being had to the accompanying drawings in which—

Figure 1 is a side elevation of my improved wagon in its normal position,

Fig. 2 is a front elevation of Fig. 1 drawn on an enlarged scale,

Fig. 3 is a view of similar nature to Fig. 40 1 showing the body portion in a dumping or tilted position and showing how rocks or can be loaded by pulling the same into the lowered end of the body portion,

Fig. 4 is a top plan view of the frame 45 structure with the body portion and overhead structure removed,

Fig. 5 is a fragmentary elevation showing 50 an extreme tilted position which the body portion can attain if it is necessary to increase the tilting angle to a greater extent than that illustrated in Fig. 3,

Fig. 6 is an enlarged fragmentary section taken on the line 6—6 of Fig. 2, and

Fig. 7 is a fragmentary side elevation 55 showing a modified form of mounting for the wagon body and illustrating in full lines

the normal position of said body and in dotted lines the tilted position of the body.

Referring to Figs. 1 to 6, inclusive, my improved wagon includes a frame 8 which is preferably made of metallic tubing or pipe. The frame 8 has two crossed portions 9 and 10 which form a support for the body 11 adjacent its forward ends. The portion 9 leads from a fitting 12 on one side of the body portion adjacent its top and extends downwardly and forwardly at an incline, as shown at 13; it then extends under the body 11 and then forwardly at a forward incline to form a part 9^a of a standard or trestle 14. In a similar manner the portion 10 has a part 15 which is connected to a fitting 16 on the opposite side of the body 11 adjacent its top and extends forwardly and downwardly at an angle and crosses the portion 9 to the opposite side of the body and then extends upwardly and forwardly at an incline, as shown at 10^a to provide a portion of said standard 14 oppositely disposed to the portion 9^a.

The portions 9^a and 10^a adjacent their tops are bent toward each other and connected together at their tops by a bolt 17, said bolt also connecting together the tops of two other pipes 18 and 19 which extend downwardly at oppositely disposed inclines for a part of their length and then extend in vertical directions as shown at 20 and 21 respectively. The lower portions of the pipes 18 and 19 are bent rearwardly at 90 either side of the body 11 and then extend upwardly at an incline as shown at 22 and are connected to the respective fittings 12 and 16. It will thus be seen that the pipes 18 and 19 form a part of the frame 8 and that the frame 8 includes as an integral part, a part of the standard or trestle 14.

The fittings 12 and 16 form a bearing for the portions 23 and 24 of the rear axle 25, said portions 23 and 24 having the rear 100 wheels 26 thereon. The axle 25 includes a depending or underslung yoke 27 which has parts 28 which straddle the sides of the body 11 and an underportion 29 which extends across the bottom of the body 11. Cleats 105 30 are secured to the bottom of the body 11 and form bearings for the part 29 of the axle 25 and serve as a support for the body 11 between its forward and rear ends. It will be understood that the part of the body 11 between its rear axle connection and the front end is of greater weight than that be-

tween the rear end and its connection to the rear axle.

Two parallel beams 31 and 32 are secured to the portions 33 and 34 of the pipes 18 and 19, respectively, by bolts 31^a (see Fig. 2) and are spaced apart to provide a guideway for the front axle 35. A king bolt 36 extends through the beams 31 and 32 and also through the front axle 35. The axle 35 slants downwardly in opposite directions from the portion through which the king bolt 36 extends. The extreme outer ends of the axle 35 are bent upwardly to provide arms 37 to provide bearings for the upper ends of movable sections 38 which directly support the front wheels 39, the lower ends 40 of said sections 38 are mounted in a beam section 41 which forms a part of the front axle 35; said beam section being secured by rivets 42 to the oppositely inclined portions of said axle 35. A pivot bolt 43 has a yoked upper end 44 which has eyelets 45 spanning the beams 31 and 32 and through which the king bolt 36 passes. The pivot bolt 43 extends through a slot 46 in the beam section 41 and has nuts 47 thereon for sliding engagement with the lower edge 48^a of the beam section 41; said edge 48^a being curved to permit the pivot bolt 43 to swing on the king bolt 36 as a pivot. The intermediate portion of the pivot bolt 43 extends through a hole 47^a in a section 48 of a shaft 49, said shaft also including a section 50 which is pivoted at 51 to the section 48 to permit said section 50 to be raised and lowered. The section 48 of the shaft 49 at portions at opposite sides of the pivot bolt 43 has rods 52 and 53 connected thereto. These rods are connected to cross arms 54 on the sections 38 of the front axle 35. Thus by turning the shaft 49 on the pivot bolt 43, the axle sections 38 will be turned in their bearings and thereby cause the front wheels 39 to steer the wagon.

Two parallel bars 55 and 56 extend transversely across the standard 14 and are secured to the portions 20 and 21 of the frame pipes 18 and 19. A block 57 is slidably mounted on the bars 55 and 56 and supports a sheave pulley 58. The bar 56 has a number of holes 59 therein which are spaced apart and a pin 60 is adapted to be inserted through a hole in the block 57 and through any of the holes 59 in the bar 56. Thus the block 57 can be slid along the bars 55 and 56 and secured in position by the pin 60. The upper end of the block 57 forms a pivot bearing for a boom 61 which has a slot 62 in which is mounted another sheave pulley 63. Another pulley 64 is mounted on the boom 61 adjacent its top and a cable 65 passes over the pulleys 58, 63 and 64 and around a block pulley 66. After passing around the block pulley 66, the cable is attached to an arm 67 on the boom 61. An-

other cable 65^a has one end attached to the arm 67 and then passes over a guide pulley 68 mounted on the top of the trestle 14.

A windlass 69 includes a winding roller 70 upon which is wound the opposite end 70 of the cable 65^a. A handle 71 is attached to the winding roller 70 and a pawl and ratchet 72 and 73 are provided to prevent the winding roller 70 from accidentally turning in an opposite direction when the cable 65 is 75 being wound thereon for a purpose herein-after described.

The block pulley 66 includes a hook 74 which can be attached to the forward end of the body 11 so that by turning the winding roller 70 the body portion can be tilted. The cable and block pulley can also be arranged, as shown in Fig. 3, and when thus used an auxiliary pulley block 75 is provided and will serve for dragging rocks, 85 such for example as the rock illustrated at 76, into the body portion 11. The boom and cable can also be used as a direct hoisting means and since the block 57 can be detachably secured at any position within the 90 lengths of the bars 55 and 56, it is possible to swing the boom at various angles to facilitate loading of the wagon.

It will be further noted that by providing the front axle 35, as above described, it will 95 swing on the king bolt 36 between the beams 31 and 32 so that any variation or irregularities in the ground will not cause the lateral tilting of the frame and body portion.

In the form of my invention shown in Fig. 7, instead of having the underslung yoke portion of the rear axle, I provide a straight axle 77 and provide two slotted extensions 78 on the frame 79. The body portion 80 has trunnions 81 thereon adapted to ride within the slots 82 in the extensions 78 and I preferably make the slots 82 arcuate with a radius equal to the distance of the point of contact of the rear end of the body 110 80 with the ground, such point of contact being shown at 83 when the body portion is in a tilted position. Thus the trunnions 81 will smoothly ride within the slots 82 to permit the body to be released at various 115 angles.

The free end 65^a of the cable 65 can be pulled by a horse or other power for hoisting or loading purposes or for tilting and dumping of the body 11.

While I have described my invention as taking a particular form, it will be understood that the various parts of my invention may be changed without departing from the spirit thereof, and hence I do not limit myself to the precise construction set forth, but consider that I am at liberty to make such changes and alterations, as fairly come within the scope of the appended claims.

Having thus described my invention, what 130

I claim as new and desire to secure by Letters Patent is:

1. A wagon of the character described including a body portion; a frame having parts extending upwardly to provide a standard; guiding means on said standard; a block slideable on said guiding means whereby the block can be moved into various positions; a hoisting boom supported by said block; a hoisting cable connected to said boom; and means on said standard for moving said boom in various angular positions; substantially as described.

2. A wagon of the character described including a body portion; a frame having parts extending upwardly to provide a standard; a transversely extending bar on said standard; a block slideable on said bar; means for adjustably securing said block to the bar in various positions thereon; a hoisting boom having its lower end supported on said block; pulleys on said boom; a hoisting cable connected to said boom; and means for moving said boom into various angular positions; substantially as described.

3. A wagon of the character described including a body portion; a frame including members extending longitudinally adjacent the sides of said body portion, and other members crossing under the bottom of said body portion and then extending upwardly to a position above said body portion, the longitudinal members extending beyond said upwardly extending portions of the first mentioned members and then extending upward and secured to said first mentioned members to provide a standard; and hoisting means supported by said standard; substantially as described.

4. A wagon of the character described including a body portion; a frame including members extending longitudinally adjacent the sides of said body portion, and other

members crossing under the bottom of said body portion and then extending upwardly to a position above said body portion, the longitudinal members extending beyond said upwardly extending portions of the first mentioned members and then extending upward and secured to said first mentioned members to provide a standard; hoisting means supported by said standard; said frame including means providing a rear axle bearing; an axle supported in said bearing; wheels on said axle; a front axle secured to said frame; and wheels on said front axle; substantially as described.

5. A wagon of the character described including a body portion; a frame including members extending longitudinally adjacent the sides of said body portion, and other members crossing under the bottom of said body portion and then extending upwardly to a position above said body portion, the longitudinal members extending beyond said upwardly extending portions of the first mentioned members and then extending upward and secured to said first mentioned members to provide a standard; hoisting means supported by said standard; said frame including means providing a rear axle bearing; an axle supported in said bearing; wheels on said axle; a front axle secured to said frame; wheels on said front axle; and means pivotally connecting said rear axle to the body portion whereby said body portion can be moved on its pivot into a dumping position by connection to said hoisting means; substantially as described.

In testimony whereof I have signed my name to this specification in the presence of two subscribing witnesses.

JOSEPH H. JASPER.
